UNITED STATES PATENT OFFICE

JOHN W. ECKLES, OF SAN ANTONIO, TEXAS

PIPE PUSHER

Application filed July 29, 1932. Serial No. 626,106.

This invention relates to a machine for pushing service pipes under sidewalks, street, tracks, etc.

Various machines have been devised for this purpose but they have not been satisfactory because the slightest wear has made them unfit for use because it has not been possible to hold the pipe in the proper direction or to maintain the machine in correct position.

13. It is an object of the present invention to provide a simple and compact machine which will stand up under excessive use and wear and at all times properly hold and guide a pipe while being pushed through the ground.

15. Another object is to provide efficient means for gripping the pipe during the pushing operation.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

55. In said drawings:

Figure 1 is a vertical longitudinal section through the machine, the same being shown in use.

Figure 2 is a plan view of the machine.

35. Figure 3 is a section on line 3—3, Figure 1.

Figure 4 is a section on line 4—4, Figure 1.

Referring to the figures by characters of reference, 1 designates a pedestal of steel or other suitable material having oppositely extended base flanges 2, one of which can be used for anchoring the structure while in use. Formed with the pedestal is a tubular guide 3 having a longitudinal slot 4 in the top thereof. Upstanding side plates 5 are welded or otherwise connected to the guide at the sides of the slot and cooperate with an arcuate plate 6 to form a housing for the gears of the machine.

50. Slidable in guide 3 is a tube 7, and welded or otherwise connected thereto is a rack 8

extending longitudinally of the tube and movable in slot 4. A gear 9 is journaled between plates 5 and meshes with rack 8. It also meshes with a smaller gear 10 secured to a shaft 11 which is journaled in plates 5 and extends laterally therebeyond. Any suitable means, such as a crank 12 or a hand wheel can be connected to either or both ends of the shaft rotating it.

65. A reversible pawl 13 is mounted between the plates 5 and is adapted to engage the rack 8 to hold it against retrograde movement. This pawl has a handle 14 at the outer side of one of the plates 5 and by means thereof the pawl can be shifted readily.

70. A head 15 is screwed on or otherwise secured to one end of tube 7 and has an integral yoke 16 the open end of which is bridged by a block 17 having a stationary vise jaw 18. A movable jaw 19 is mounted between guides 20 in yoke 16 and has an adjusting screw swiveled thereto and engaging the yoke.

75. In practice an excavation E is made where the pipe is to be actuated, and the machine is set up in a recess R formed in the bottom of the excavation. One flange 2 will press into the wall of the recess, as shown. The pipe P is inserted end first into tube 7 and a bit B is placed on the front or advancing end of the pipe. Tube 7 is retracted within guide 3 and the pipe is then gripped between jaws 18 and 19. By then rotating the gears the pipe will be pushed forwardly, the pawl 13 cooperating with the rack 8 to prevent retrograde movement. The pawl is then reversed, the jaws disengaged from the pipe, the guide tube 7 again retracted and the foregoing operation repeated to again advance the pipe.

80. 85. 90. 95. 100. What is claimed is:

1. A pipe-pushing machine including a tubular guide, a pedestal therefor having anchoring means, a tubular pipe holder slidable in the guide, a rack thereon, gearing for actuating the rack, and pipe-gripping means on the holder.

2. A pipe-pushing machine including a tubular guide, a pedestal therefor having anchoring means, a tubular pipe holder slidable in the guide, a rack thereon, gearing for

actuating the rack, pipe-gripping means on the holder, and means for holding the rack against retrograde movement.

3. A pipe-pushing machine including a pedestal, an anchoring flange thereon, a tubular guide carried by the pedestal, a tubular pipe holder slidable in the guide, a rack on said holder, gearing for operating the rack,

a yoke on the holder, a fixed jaw therein, and a movable jaw in the yoke, said jaws co-operating to grip a pipe projecting from the holder.

In testimony that I claim the foregoing as my own, I have hereto affixed my signature.

JOHN W. ECKLES.
